(57) **CLAIM**

The ornamental design for a dual chamber fluid dispenser, as shown and described.

DESCRIPTION

FIG. 1 is an exploded perspective view of a dual chamber fluid dispenser showing my new design;

FIG. 2 is a perspective view of the dual chamber fluid dispenser;

FIG. 3 is an enlarged front elevational view of FIG. 2, the rear elevational view being identical thereto;

FIG. 4 is a top plan view of FIG. 3, the bottom plan view being identical thereto.

FIG. 5 is a left side elevational view of FIG. 3;

FIG. 6 is a right side elevational view of FIG. 3;

FIG. 7 is an enlarged front elevational view of the dual chamber fluid dispenser shown with the cap removed, the rear elevational view being identical thereto;

FIG. 8 is a top plan view of FIG. 7, the bottom plan view identical thereto;

FIG. 9 is a left side elevational view of FIG. 7;

FIG. 10 is a right side elevational view of FIG. 7;

FIG. 11 is an enlarged front elevational view of the fluid insert of the dual chamber fluid dispenser shown separately for clarity of illustration, the rear elevational, top and bottom plan views being identical thereto;

FIG. 12 is a left side elevational view of FIG. 11;

FIG. 13 is a right side elevational view of FIG. 11;

FIG. 14 is an enlarged front elevational view of the fluid inserts and end cap of the dual chamber fluid dispenser, the rear elevational view being identical thereto;

FIG. 15 is a top plan view of FIG. 14, the bottom plan view being identical thereto;

FIG. 16 is a left side elevational view of FIG. 14;

FIG. 17 is a right side elevational view of FIG. 14;

FIG. 18 is an enlarged front elevational view of the casing of the dual chamber fluid dispenser, the rear elevational view being identical thereto

FIG. 19 is a top plan view of FIG. 18, the bottom plan view being identical thereto;

FIG. 20 is a left side elevational view of FIG. 18; and,

FIG. 21 is a right side elevational view of FIG. 18.
